John Tealy's
Design of Ornament for Hats.

Nº 3651

PATENTED
AUG 31 1869

John Tealy Jr.

W. M. Gooding } attat
Edward Gilman }

United States Patent Office.

JOHN SEALY, JR., OF NEWARK, NEW JERSEY.

Design No. 3,651, dated August 31, 1869.

DESIGN FOR AN ORNAMENT FOR A CHILD'S HAT.

The Schedule referred to in these Letters Patent and making part of the same.

Be it known that I, JOHN SEALY, Jr., of the city of Newark, in the county of Essex, and State of New Jersey, have produced or originated a new Ornament for Hats, of which the following, taken in connection with the accompanying drawings, is a full, clear, and exact description.

Of thin sheet-metal, the form of a bow-knot is formed, with its surface corrugated, as shown in Figure 2. A bright bead, being placed upon a small centre-piece of metal, of circular form, is put upon the knot, and the whole is attached to the band of the hat, as shown in Figure 1.

A button, Figure 3, formed of thin sheet-metal, with its surface covered with forms of pointed leaflets, and surmounted by a bright bead, is placed over crossing-cords in the centre of the crown, as shown in fig. 1.

What I claim, and desire to secure by Letters Patent, is—

The design in the form of the bow-knot and of the button, as a new ornament for a hat.

JOHN SEALY, Jr.
